4 Claims. (Cl. 62—119.5)

1

My invention relates to refrigeration systems of the absorption type and is especially useful in such systems employing an inert gas or auxiliary pressure equalizing agent.

It is an object of my invention to effect improvements in the manner in which fluids are circulated in systems of this type, particularly to provide new arrangements for analyzing vapor generated in the vapor expulsion unit and passing to the condenser in order to eliminate absorption liquid vapor from refrigerant vapor and reduce heat losses in the system. More particularly, it is an object to provide such new arrangements for analyzing generated vapor in which the heat recovered in the analyzer is effectively utilized in the refrigeration system and loss of recovered heat by radiation is minimized. Further, it is an object to embody the analyzer in a compact manner in the vapor expulsion unit without the requirement or need of increasing the overall size of the unit to any appreciable extent by reason of the fact that provision is made for analyzing generated vapor.

The novel features which I believe to be characteristic of my invention are set forth with particularity in the claims. The invention, both as to organization and method, together with the above and other objects and advantages thereof, will be better understood by reference to the following description taken in connection with the accompanying drawings forming a part of this specification, and of which:

Fig. 1 diagrammatically illustrates an absorption refrigeration system embodying the invention;

Fig. 2 is a fragmentary view of a refrigeration system like that shown in Fig. 1 diagrammatically illustrating another embodiment of the invention; and

Fig. 3 is a fragmentary view illustrating one practical form of carrying out the embodiment shown in Fig. 2.

Referring to Fig. 1, I have shown my invention in connection with an absorption refrigeration system of a uniform pressure type which is well known in the art and in which an inert pressure equalizing gas is employed. Such a refrigeration system comprises a generator or vapor expulsion unit 9, including a generator or boiler 10 containing a refrigerant, such as ammonia, in solution in a body of absorption liquid, such as water. Heat is supplied to the boiler 10 from a heating tube or flue 11 thermally connected therewith at 12, as by welding, for example. The heating tube 11 may be heated in any suitable

2

manner, as by an electrical heating element disposed within the lower part of the tube 11 or by a liquid or gaseous fuel burner which is adapted to project its flame into the lower end of the tube.

The heat supplied to the boiler 10 and its contents expels refrigerant vapor out of solution, and, in a manner to be described presently, the refrigerant vapor passes upwardly from the vapor expulsion unit 9 through an air cooled rectifier 13 into an air cooled condenser 14 in which it is condensed and liquefied. Liquid refrigerant flows from condenser 14 through a conduit 15 into a cooling element 16 in which it evaporates and diffuses into an inert pressure equalizing gas, such as hydrogen, which enters through a conduit 17. Due to evaporation of refrigerant fluid into inert gas, a refrigerating effect is produced with consequent absorption of heat from the surroundings.

The rich gas mixture of refrigerant vapor and inert gas formed in cooling element 16 flows from the upper part thereof through a conduit 18, one passage of a gas heat exchanger 19, conduit 20 and absorber vessel 21 into the lower end of an absorber coil 22. In absorber coil 22 the rich gas mixture flows counter-current to downwardly flowing absorption liquid which enters through a conduit 23. The absorption liquid absorbs refrigerant vapor from inert gas, and inert gas weak in refrigerant flows from absorber coil 22 in a path of flow including conduit 24, another passage of gas heat exchanger 19 and conduit 17 into the lower part of cooling element 16.

The circulation of gas in the gas circuit just described is due to the difference in specific weight of the columns of gas rich and weak, respectively, in refrigerant vapor. Since the column of gas rich in refrigerant vapor and flowing from cooling element 16 to the absorber coil 22 is heavier than the gas weak in refrigerant and flowing from the absorber coil 22 to cooling element 16, a force is produced or developed within the system for causing circulation of inert gas in the manner described.

Absorption solution enriched in refrigerant flows from the absorber vessel 21 through a conduit 25 and an inner passage or pipe 26 of liquid heat exchanger 27 disposed about the lower part of the vapor expulsion unit 9. As will be described presently, liquid flows from the inner pipe 26 of the liquid heat exchanger into the lower end of a vapor lift pipe or tube 28 in thermal exchange relation with the heating tube 11 at 29, as by welding, for example. Liquid is raised

by vapor-liquid lift action through pipe 28 into the upper part of boiler 10. Refrigerant vapor expelled out of solution in boiler 10, together with refrigerant vapor entering through pipe 28, flows upwardly from the vapor expulsion unit 9 to the condenser 14, as previously explained. The absorption liquid from which refrigerant vapor has been expelled flows from the boiler 10 through the outer pipe or passage 30 of liquid heat exchanger 27 and conduit 23 into the upper part of absorber coil 22. The circulation of absorption solution in the liquid circuit just described is effected by raising of liquid through pipe 28.

The outlet end of condenser 14 is connected by an upper extension of conduit 15, vessel 31 and conduit 32 to a part of the gas circuit, as at one end of heat exchanger 19, for example, so that any inert gas which may pass through the condenser 14 can flow into the gas circuit. Refrigerant vapor not liquified in the condenser flows through the upper part of conduit 15 to displace inert gas in vessel 31 and force such gas into the gas circuit. The effect of forcing gas into the gas circuit in this manner is to raise the total pressure in the entire system whereby an adequate condensing pressure is obtained to insure condensation of refrigerant vapor in condenser 14.

In accordance with my invention I provide an analyzer 33 which is arranged in a compact manner at the vapor expulsion unit 9 and more or less forms a unitary part thereof. The analyzer 33 is formed by the horizontally extending portion of an L-shaped conduit 34 which is closed at both ends and to one closed end of which is connected the upper end of the inner pipe or passage 26 of the liquid heat exchanger. Absorption solution from the absorber vessel 21 enters one end of the horizontal portion 33 of conduit 34, and the lower end of the vapor lift tube 28 is connected to the lower closed end of the vertical portion 35 of conduit 34 to receive absorption solution to be raised by vapor lift action into the upper part of the boiler 10. The boiler 10 is formed by one leg of an inverted U-shaped conduit whose other leg 36 is connected at its lower end to the analyzer 33 at a region removed from the point at which the liquid heat exchanger pipe 26 is connected thereto. At a region adjacent to the closed end of the horizontally extending portion 33 of conduit 34 is connected a conduit 37 which forms a part of the vapor supply line leading upwardly from the vapor expulsion unit 9 to the condenser 14.

The vapor expulsion unit 9 and absorber including the vessel 21 and coil 22 form a circuit for absorption solution in the boiler 10 of which a column of liquid is maintained at a height, such as indicated in Fig. 1, for example, so that absorption liquid will flow by gravity through a connection or tube 38 into the outer pipe or passage 30 of the liquid heat exchanger and conduit 23 into the upper part of the absorber coil 22. The absorption liquid flowing downwardly by gravity through the absorber coil 22 passes into the absorber vessel 21 in which the enriched absorption solution is maintained at a level, such as indicated in Fig. 1, for example. The analyzer or horizontally extending portion 33 of the L-shaped conduit 34 is at or slightly below the liquid level maintained in the absorber vessel 21, so that the analyzer will be completely filled with absorption solution during operation of the refrigeration system. In effect, the liquid contained in the conduit 34 freely communicates with the store of absorption solution in the absorber vessel 21 through a solid and unbroken liquid body.

In the operation of the refrigeration system of Fig. 1, vapor generated in the vapor lift tube 28 and boiler 10 passes from the upper end of the boiler into the conduit 36. The generated vapor usually is a mixture of refrigerant vapor and absorption liquid vapor; and, when ammonia and water are employed as the refrigerant and absorption liquid, for example, the generated vapor is usually a mixture of ammonia vapor and water vapor. Due to the difference in boiling points of ammonia and water, the water vapor may be removed from ammonia by cooling the mixture to condense out the water. In Fig. 1 this is accomplished by forcing all of the generated vapor from the conduit 36 through the liquid body in the analyzer 33.

The absorption liquid introduced into the analyzer 33 is relatively rich in refrigerant and at a lower temperature than the generated vapor, and in bubbling through the enriched absorption solution the water vapor is cooled sufficiently and condenses and in this way is removed from the ammonia vapor. The latent heat of condensation resulting from condensation of water vapor is given up to the enriched absorption solution and forms an internally heated zone in which some ammonia vapor is expelled out of solution. Such expelled refrigerant vapor mixes with refrigerant vapor generated in the vapor lift tube 28 and boiler 10, and the mixture passes from the analyzer 33 through the conduit 37 to the condenser 14.

In the embodiment of Fig. 1 it is desirable to keep the generated vapor in direct contact with the absorption solution in the analyzer 33 for a relatively long interval of time. I accomplish this by making the horizontally extending portion 33 of conduit 34 relatively long in a manner which will not necessitate unduly increasing the overall size of the vapor expulsion unit 9. In a practical form of carrying out the embodiment of Fig. 1, the horizontally extending conduit portion 33 forming the analyzer can be made as a coil which is disposed about the pipes forming the boiler 10, heating tube 11 and vapor lift tube 28, in the manner shown in Fig. 3 to be described presently. Such coil can be of any suitable length which may vary from three-quarters to one and one-half turns, for example.

It will be observed that the provision of an analyzer in a vapor expulsion unit 9 like that shown and described lends itself to an extremely compact arrangement of parts. The cluster of vertical pipes forming the vapor expulsion unit occupies a relatively small amount of space in which the individual pipes are in the immediate vicinity of one another. While the pipes in Fig. 1 are shown in spaced apart relation and in the same plane in order to facilitate an understanding of the invention, it is to be understood that in a practical embodiment these pipes may be conveniently spaced apart about the heating tube 11 so that they will occupy a minimum amount of space. The liquid heat exchanger 27 can be made in the form of a coil disposed about the lower parts of the heating tube 11 and the pipes forming the boiler 10 and vapor lift tube 28.

Even when making provision for the analyzer 33 in the vapor expulsion unit 9, there is no requirement or need for further increasing the overall size of the unit on account of such analyzer because the outer diameter of the analyzer, when in the form of a coil, need not be greater than that of the liquid heat exchanger, as seen in Fig. 3. Hence, the analyzer 33 in Fig. 1 can be embedded in the same body of insulat-

ing material which thermally insulates the other parts of the vapor expulsion unit, in the manner shown in Fig. 3, thereby providing an efficiently insulated vapor expulsion unit in which provision is made for analyzing generated vapor. This is especially important in that the heat recovered in the form of latent heat of condensation in the analyzer 33 can be efficiently utilized and loss of such recovered heat from the refrigeration system will be minimized.

Essentially, the absorber coil 22 constitutes an externally cooled zone while the vapor lift tube 28 and boiler 10 each may be referred to as an externally heated zone of the absorption liquid circuit. In Fig. 1 it will be seen that the externally heated zones formed by the vapor lift tube 28 and boiler 10 are vertically extending and overlap each other in a vertical direction. The thermal connections of boiler 10 and vapor lift tube 28 to the heating tube 11 are formed along lines extending parallel to the axis of the heating tube, such thermal connections extending downwardly from a region above the highest point of the liquid heat exchanger 21. The heat conductive connection of the vapor lift tube 28 to the heating tube 11 extends along a vertical distance of which at least one part is farther from the lower heat input end of the heating tube 11 than the point of the heat conductive connection of the boiler 10 to the heating tube 11 which is nearest to the lower end of the heating tube.

In the embodiment just described, the relation of the liquid heat exchanger to the pipes of the vapor expulsion unit and the conduit forming the analyzer 33 is such that any vapor bubbles which may form in the liquid heat exchanger can freely vent through the connection 38 into the boiler 10 and from the liquid heat exchanger pipe 26 into the analyzer 33. In this way the absorption solution circulation never can be blocked in the circuit by trapped vapor.

It will also be seen that generated vapor from the conduit 36 passes through liquid in the analyzer 33 with practically no liquid head on the vapor. This has certain advantages in that no appreciable resistance to lifting of liquid in the vapor lift tube 28 is developed. This will be apparent when it is considered that the reaction head for lifting liquid in the vapor lift tube 28 is contained in the vapor expulsion unit itself and extends downwardly from the liquid level in the analyzer 33, which is substantially the same as the liquid level in the absorber vessel 21, to a level corresponding to about the point 39 at the lower end of the vapor lift tube 28. In order to obtain efficient lifting of liquid in the vapor lift tube 28 under these conditions, the externally heated zone formed by the lift tube is developed as a gas lift pump having a vapor forming part of which vapor is produced by heating to effect such lightening of the fluid column in the lift tube that pumping of liquid will be promoted under the reaction head in the vapor expulsion unit.

In the embodiment of Fig. 1 the heating tube 11 is formed with a slit 40 at which the upper ends of the thermal connections of the boiler 10 and vapor lift tube 28 to the heating tube terminate. By forming such a slit 40 the flow of heat to and through the upper parts of the heating tube 11 is reduced, particularly when the lower end of the tube 11 is arranged to be heated by an electrical heating element. In this way the upper parts of the boiler 10 which do not con-

tain liquid are not heated to such a high temperature that generated vapor therein will become superheated. By preventing superheating of generated vapor, the normal condensation of vapor in other parts of the refrigeration system will not be disturbed.

In the embodiment of Fig. 1 the vapor lift tube 28 receives absorption solution which is relatively rich in refrigerant and which therefore may be referred to as a "rich liquid pump." In Fig. 2 I have shown an embodiment of the invention which differs from that of Fig. 1 in that the vapor lift tube therein receives absorption solution which is relatively weak in refrigerant and which may be referred to as a "weak liquid pump." In Fig. 2, in which parts similar to those shown in Fig. 1 are referred to by the same reference numerals, absorption solution enriched in refrigerant and flowing from the absorber 21 to the vapor expulsion unit 9a passes from the inner pipe 26 of the liquid heat exchanger 21 into a vertically extending pipe 41 at a point 42 which is at a level below the liquid level in the absorber vessel 21 and the level of the column of liquid contained in the pipe 41.

The extreme lower end of pipe 41 is closed in the same manner as the boiler pipe 10 in Fig. 1, and the lower part or section 10a thereof is in good thermal contact with the heating tube 11a, as by welding, for example, as indicated at 12a. To the lower end of pipe 41 is connected the lower end of vapor lift tube 28a which is in thermal contact with the exterior of the heating tube along a line extending upwardly to the slit 40a, such thermal contact in this instance extending upwardly a greater distance than the thermal contact of section 10a of the pipe 41.

Liquid is raised through vapor lift tube 28a to the upper part of a standpipe or riser 43 whose lower end is connected to the outer passage or pipe 30 of the liquid heat exchanger 21. The heating tube 11a in normal operation heats enriched absorption solution in the pipe section 10a to cause expulsion of refrigerant vapor from solution. The principal part of generated vapor produced in the vapor expulsion unit of Fig. 2 is expelled from solution in pipe section 10a, and liquid of decreasing concentration flows downwardly in the section 10a to the bottom closed end thereof. In certain instances it is desirable to provide a thermal gap or air space 44 between the lower portion of the pipe section 10a and the heating tube 11a. In this way excessive expulsion of refrigerant vapor from solution in the lower part of pipe section 10a is prevented, thereby avoiding undesirable decrease in concentration of the absorption solution and consequent increase in its temperature.

A liquid column is maintained in the riser 43 which is at a level corresponding to the liquid level in boiler 10 of Fig. 1, so that absorption solution weak in refrigerant can flow by gravity from the lower end of the riser to the upper part of the absorber coil through the outer passage 30 of liquid heat exchanger 21 and conduit 23. The pipe 41 at a region above the bottom section 10a is formed to provide a horizontally extending section 38a which is utilized as the analyzer of the vapor expulsion unit. From the pipe section 38a the pipe 41 extends upwardly to the condenser and communicates therewith, such upper pipe section 37a forming the vapor supply leading to the condenser and corresponding to the conduit 37 in Fig. 1.

Vapor expelled from solution in pipe section 10a passes upwardly through the analyzer 38a

in which it is analyzed and refrigerant vapor flows through the pipe section 37a to the condenser in which it is liquefied, as explained above in connection with Fig. 1. The vapor which passes from the upper end of vapor lift tube 28a into the vapor space of riser 43 flows therefrom through a conduit 45 into the lower part of the horizontally extending pipe section or analyzer 33a. The vapor entering the analyzer 33a from the conduit 45 bubbles through enriched absorption solution and is analyzed, whereby absorption liquid vapor will be removed from refrigerant vapor, as explained above in connection with the embodiment of Fig. 1.

In the embodiment of Fig. 2, it will be seen that vapor passing through conduit 45 is introduced into the analyzer 33a below the liquid surface level of the column of enriched absorption solution therein. While the vapor in conduit 45 and the vapor space of the riser 43 must overcome the liquid head extending upwardly from the point that conduit 45 is connected to the analyzer 33a and the resistance to lifting of liquid in the vapor lift tube 28a is increased, this has not been found objectionable and refrigeration systems which have been constructed and embody vapor expulsion units generally like the one illustrated in Fig. 2 have been satisfactory in operation.

The embodiment of Fig. 2 possesses certain advantages in that the boiler section 10a, analyzer section 33a and vapor supply line can be formed from a single continuous length of piping, thereby providing an extremely simple and inexpensive construction. A practical form of vapor expulsion unit like the one shown in Fig. 2 and just described is illustrated in Fig. 3, in which similar parts are referred to by the same reference numerals. It will be seen in Fig. 3 that the liquid heat exchanger 27 is in the form of a coil disposed about the pipes extending downwardly to the lower part of the vapor expulsion unit, and that the analyzer 33a is developed as a turn or coil which envelops the vapor expulsion unit piping. While the pipes are shown as being alongside one another, it will be understood that the component parts are distributed as symmetrically as possible about the heating tube 11a.

It will be seen that in Figs. 2 and 3 the pipe providing the boiler section 10a and vapor lift tube 28a and heating tube 11a are disposed alongside one another and extend together as a group or cluster in an upward direction to a region at least as high as the upper end of the vapor lift tube 28a. Likewise, in Fig. 1 the boiler pipe 10, vapor conducting connection 36, vapor lift tube 28 and heating tube 11 form a similar group or cluster of pipes and conduits. Further, in both embodiments of Fig. 1 and of Figs. 2 and 3 the analyzing portions 33 and 33a and liquid heat exchangers 27, which are disposed about the heating tubes 11, essentially form a part of such group or cluster of pipes and conduits serving as component parts of the vapor expulsion unit.

The vapor expulsion unit in its entirety, together with the liquid heat exchanger 27 and analyzer 33a, are embedded in a single body 46 of insulating material retained in a metal shell or casing 47 having openings at the top and bottom through which the ends of the heating tube 11a project.

In vapor expulsion units of the kind shown in Figs. 2 and 3, it is desirable to develop the units in such manner that they can be tilted to a considerable extent and yet avoid the liquid level in pipe 41 falling below the point 42 at which the liquid heat exchanger pipe 26 is connected

thereto. This result is obtained by arranging the absorber vessel 21 at a relatively high level. However, the absorber vessel 21 should not be arranged at such a high level that the liquid surface level therein is such a distance above the connecting point of conduit 45 to the analyzer 33a to render the vapor lift tube 28a ineffective to lift liquid. Hence, in carrying out the embodiment of Fig. 2 in practice, it will be understood that a proper relation of the levels indicated at I, II and III in Fig. 2 is essential for satisfactory operation.

In view of the foregoing, it will now be understood that a new arrangement for circulating fluids in an absorption refrigeration system has been provided which is efficient in operation, simple in construction and inexpensive to manufacture. In the embodiments described above, generated vapor is analyzed by bubbling such vapor through and in counter-flow to enriched absorption solution passing from the absorber to the vapor expulsion unit. Hence, generated vapor is analyzed by passing directly in contact with absorption solution circulating in an active part of the solution circuit. By way of example and without limitation, the point 42 at which the liquid heat exchanger pipe 26 is connected to pipe 41 may be approximately midway between the liquid level in the absorber vessel 21 and the point at which the vapor conduit 45 is connected to the analyzer or pipe section 33a.

While several embodiments of the invention have been shown and described, it will be apparent that modifications and changes may be made without departing from the spirit and scope of the invention as pointed out in the following claims.

What is claimed is:

1. In absorption refrigeration apparatus having a refrigerant vapor supply line, a circuit for circulation of absorption solution including an absorber and a vapor expulsion unit comprising an upright heating tube having a lower heat input end, a vertically extending pipe which serves as a boiler vessel and is in communication with said vapor supply line, conduit means for conducting solution from said vapor expulsion unit to the inlet of said absorber including a lift tube having the lower end thereof communicating with the lower part of said pipe, said pipe and lift tube and heating tube being disposed alongside one another and extending together as a group or cluster in an upward direction to a region at least as high as the upper end of said lift tube, said pipe and lift tube being in thermal relation with the exterior of said heating tube, conduit means connecting the outlet end of said absorber and said pipe at one level which is intermediate the ends of the latter for flowing solution by gravity in an unbroken stream from the absorber outlet through said pipe into the lower end of said lift tube and forming a liquid column in said pipe having a liquid surface above said one level, and vapor conducting means to conduct vapor generated in said vapor expulsion unit to a region of said pipe below said one level and above the connection of said lift tube thereto for flowing vapor in intimate contact with absorption solution in a part of said pipe which serves as an analyzer, said last-mentioned analyzer part of said pipe essentially forming a part of said group or cluster.
2. In absorption refrigeration apparatus having a refrigerant vapor supply line, a circuit for circulation of absorption solution including an

absorber and a vapor expulsion unit comprising an upright heating tube, a first vertically extending conduit which serves as a boiler vessel and is in communication with said vapor supply line, conduit means for conducting solution from said vapor expulsion unit to said absorber including a second vertically extending conduit and a lift tube having the lower end thereof communicating with the lower part of said first conduit and the upper end thereof communicating with the upper part of said second conduit, said first and second conduits and lift tube and heating tube being disposed alongside one another and extending together as a group or cluster in an upward direction to a region at least as high as the upper end of said lift tube, said first conduit and lift tube being in thermal relation with the exterior of said heating tube, conduit means connecting the outlet end of said absorber and said first conduit at one level which is intermediate the ends of the latter for flowing solution by gravity in an unbroken stream from the absorber outlet through said first conduit into the lower end of said lift tube and forming a liquid column in said first conduit having a liquid surface above said one level, and vapor conducting means to conduct vapor from the upper part of said second conduit to a region of said first conduit below said one level and above the connection of said lift tube thereto for flowing vapor in intimate contact and in counterflow to absorption solution in a part of said first conduit which serves as an analyzer, said last-mentioned analyzer part of said first conduit essentially forming a part of said group or cluster.

3. In absorption refrigeration apparatus having a refrigerant vapor supply line, a circuit for circulation of absorption solution including an absorber and vapor expulsion unit and a vertically extending liquid heat exchanger connected therebetween, said vapor expulsion unit comprising an upright heating tube having a lower heat input end and piping in the immediate vicinity of such heating tube comprising a plurality of sections including a first vertical section which serves as a gas lift pump and a second section which is in communication with said refrigerant vapor supply line and to the lower part of which said gas lift pump section is connected, conduit means including said liquid heat exchanger which is disposed about said heating tube and connects the outlet end of said absorber and said other piping section for flowing solution in an unbroken stream from the absorber outlet through said liquid heat exchanger and second piping section into the lower end of said first gas lift pump section and forming a liquid column in said second piping section freely communicating with liquid in the absorber, said first gas lift pump section having a part in which vapor is formed which is thermally connected to the exterior of said heating tube in a zone extending downwardly below the highest point of said liquid heat exchanger, means including a third piping section for conducting vapor generated in said vapor expulsion unit to said second piping section for flowing vapor in intimate

contact with enriched absorption solution in an analyzing portion of the second piping section and thereafter to said refrigerant vapor supply line and said first and third piping sections and heating tube being disposed alongside one another and extending as a group or cluster in an upward direction to a region at least as high as the upper end of said first gas lift section, the analyzing portion of said second piping section and said liquid heat exchanger essentially forming a part of said group or cluster.

4. In absorption refrigeration apparatus having a refrigerant vapor supply line, a circuit for circulation of absorption solution including an absorber and vapor expulsion unit and a vertically extending liquid heat exchanger connected therebetween, said vapor expulsion unit comprising an upright heating tube having a lower heat input end, a vertically extending pipe in thermal relation with said heating tube which serves as a boiler vessel and is in communication with said vapor supply line, conduit means for conducting absorption solution from said vapor expulsion unit to the inlet of said absorber including said heat exchanger and a vapor lift tube having the lower end thereof communicating with the lower part of said pipe, conduit means including said heat exchanger which is disposed about said heating tube and connects the outlet end of said absorber and said pipe at one level which is intermediate the ends of the latter for flowing solution by gravity in an unbroken stream through said heat exchanger and pipe into the lower end of said vapor lift tube and forming a liquid column in said pipe having a liquid surface above said one level, said vapor lift tube having a part thermally connected to the exterior of said heating tube in a zone extending downwardly below the highest point of said heat exchanger, vapor conducting means including a connection to conduct vapor generated in said vapor expulsion unit to a region of said pipe below said one level and above the connection of said vapor lift tube thereto for flowing vapor in intimate contact with absorption solution in a part of said pipe which serves as an analyzer, and said pipe and lift tube and vapor conducting connection and heating tube being disposed alongside one another and extending together as a group or cluster in an upward direction to a region at least as high as the upper end of said lift tube, the analyzing part of said pipe and said liquid heat exchanger essentially forming a part of said group or cluster.
